UNITED STATES PATENT OFFICE

ELMER J. KIRCHOFF, OF DETROIT, MICHIGAN

VERTICALLY AND LATERALLY MOVABLE WINDOW

Application filed August 19, 1930. Serial No. 476,414.

This invention relates to improvements in the construction of windows, particularly windows for automobiles, airplane cabins, steamship cabins, street and railway cars.

5 The primary object of the present invention is to provide a novel type of window which is designed to telescope into the frame or to be swung outwardly therefrom as desired, the window when in the latter position being disposed at an oblique angle to the wall of the structure in which it is mounted so as to act as a shield or wind deflector thus making it possible to keep the window open without permitting wind currents created by the 10 movement of the structure in which the window is mounted, to flow directly through the window opening.

Another object of the invention is to provide a novel means for raising and lowering 20 the window and for swinging the same out of its frame after it has been raised slightly beyond the normal raised position.

A further object of the invention is to provide a novel type of cover or canopy designed 25 to overlie the area between the top edge of the window when it is swung out of its frame, and the adjacent window frame.

A still further object of the invention is to provide a novel type of molding about 30 certain sides of the window frame which is shiftable, it being designed to overlie the edge of the window panel when it is in its frame and to yield for the passage of the panel when the latter is swung out of its 35 frame.

The invention will be best understood from a consideration of the following detailed description taken in connection with the accompanying drawings forming part of this 40 specification, with the understanding, however, that the invention is not confined to any strict conformity with the showing of the drawings but may be changed or modified so long as such changes or modifications 45 mark no material departure from the salient features of the invention as expressed in the appended claims.

In the drawings:

50 Figure 1 is a view in perspective of the structure embodying the present invention.

Figure 2 is a vertical longitudinal sectional view through the structure shown in Figure 1 taken on a line substantially parallel with the inner and outer faces of the door.

Figure 3 is a sectional view taken on the 55 line 3—3 of Figure 2.

Figure 4 is a detailed transverse section taken through the top of the door structure.

Figure 5 is a detailed sectional view taken 60 through the lower edge or sill of the window opening with the window closed.

Figure 6 is a detailed view of the shade roller.

Figure 7 is a sectional view taken upon the 65 line 7—7 of Figure 1.

Figure 8 is a sectional view taken upon the line 8—8 of Figure 1.

Figure 9 is a sectional view similar to Figure 4, showing a modified method of attaching the shade curtain to the clip with which 70 the window panel engages.

Referring more particularly to the drawings wherein like numerals of reference indicate corresponding parts throughout the several views, the improved window structure 75 embodying the present invention is shown as applied to a motor vehicle door, the door being indicated generally by the numeral 1. As is of course well known all motor vehicle doors are provided with a window opening 80 which is here indicated by the numeral 2 and the body of the door beneath the window opening is of hollow construction providing a chamber 3 into which the glass panel of the door may be lowered, this chamber opening into the window opening 2 through the slot 4 in the bottom of the window opening. This is the usual construction of motor vehicle doors.

In carrying out the present invention the top and rear faces of the window opening 2 are provided with the channels 5 and 6 respectively while the forward edge of the window opening is formed to provide the recess 7. These channels 5 and 6 and the recess 7 are in the same vertical plane as the slot 4 through which the glass window panel passes downwardly to the interior of the door body or into the chamber 3.

In the bottom of the recess 7 there is posi- 100

tioned a post 8 the upper end of which is secured in any suitable manner in the frame of the door while the lower end is mounted upon the piece or step 9 in the lower part of the chamber 3.

The glass panel 10 is mounted in a steel frame 11 and the forward side of this frame is connected to one edge of a toothed rack 12 which in turn is attached to a tube or sleeve 13. As shown in Figure 2 the rack 12 and the tube 13 are of a length greater than the height of the frame 11 in which the glass panel is mounted and to which they are attached, the upper ends of the tube and rack being in substantially the same plane as the top of the frame while the other ends project a substantial distance below the bottom thereof. This tube or-sleeve 13 has the post 8 extended therethrough and upon this post the sleeve is freely slideable.

The upper end of the post 8 has secured therein upon the inner side a pin 14 while the sleeve 13 has formed therein a bayonet slot 15 the outer arm of which is of gradually increasing width to its open end. The purpose of this pin and slot will become apparent as the description proceeds.

Within the chamber 3 under the window opening there is mounted in suitable bearings 16 a horizontal shaft 17 which carries upon the end nearest the post 8 a spur tooth gear 18 and a bevel gear 19. The gear 18 meshes with the teeth of the rack 12 when the window panel 10 is within the window opening 2 and when the panel is raised to close the window opening the bevel gear 19 meshes with a bevel gear 20 carried upon the lower end of the sleeve 13.

Intermediate its ends the shaft 17 has mounted thereon a spiral gear 21 which meshes with a large spiral gear 22 mounted upon the shaft 23 which extends through the inner wall of the door chamber and has mounted thereon for access from within the body on which the door is mounted, a crank handle 24.

Upon the end of the shaft remote from the gears 18 and 19 there is fixed a small drum 25 about which is a split band 26 the ends of which terminate in the upwardly extending spaced ears 27 which have apertures therethrough, one of which apertures is threaded. The band 26 serves as a brake band and the ears at the ends thereof are drawn together by a threaded shaft 28 which passes through the apertures thereof, which shaft is extended through the inner wall of the chamber beneath the window opening terminating within the vehicle in the crank handle 29. The shaft 28 is, of course, in threaded engagement only with the ear which has the threaded aperture formed therethrough. The other ear has the shaft swivelly attached thereto as shown. It will be readily seen that by rotating the crank handle 29 the ear having the threaded aper-

ture will be drawn toward the other ear and the band thus tightened about the drum so as to hold the latter against rotation.

Each of the channels 5 and 6 has therein a molding strip, the strip in the channel 5 being indicated by the numeral 30 while the strip in the channel 6 is indicated by the numeral 31.

These molding strips are hingedly secured in their respective channels at their inner corners as indicated by the numerals 32 and each has formed therein a longitudinally extending depression, the depression in the strip 30 being indicated by the numeral 33 while that in the strip 31 is indicated by the numeral 34. These longitudinal depressions in the hinged moldings are in the same vertical plane as the slot 4 through which the glass panel 10 moves so that when the panel is raised to close the window opening its rear and upper edges will position respectively in the depressions 34 and 33 of the shiftable moldings. Each of these moldings has interposed between its inner face and the bottom wall of the channel in which it is placed, a spring 35 which normally urges it outwardly as shown.

The top portion of the frame around the window opening has a chamber formed therein adjacent the inner side thereof as indicated by the numeral 36 and in this chamber there is positioned a spring controlled roller 37 which is of tapered construction, the end of greatest diameter being adjacent the free or rear edge of the window panel. This chamber 36 is accessible from the inner side of the window frame through an opening closed by a door 38 through the lower portion of which there is formed a longitudinal slot 39. Secured along one edge to the roller 37 is a curtain 40 which is of trapezoidal outline, the longitudinal edges thereof converging toward the narrow end. One of these longitudinal edges is secured to the roller. This curtain is passed from the roller out of the chamber 36 through the slot 39 and is drawn around under the top face of the frame of the window opening over a bearing roller 41, to the inner side of the channel 5 in which the top molding 30 is positioned.

This inner side of the channel 5 has a slot 42 cut in the face thereof and into this slot frictionally engages a lip 43 formed along one side of an elongated substantially U-shaped spring clip 44. This spring clip 44 is of the same length as the window opening and has its open side directed downwardly with its top normally positioning in the longitudinal recess of the top molding so that when the window panel is raised the upper edge thereof will slip into and be engaged by the clip and thus, when the panel is swung outwardly as will be hereinafter described, the curtain 40 will be unrolled from its supporting roller and drawn outwardly with the panel to cover the

area between the top edge of the panel and the top of the window opening.

Within the slot 4 which leads from the window opening into the chamber therebeneath, at the outer side of the slot, there is positioned lengthwise of the slot a spring body 45 which is in the form of a trough and opens upwardly. This trough like body is of resilient material and bears against the window panel when the same is in the window opening or is lowered in the chamber therebeneath to hold the panel against movement and consequently prevent rattling of the window. In order to prevent the entrance of rain between this body and the window panel a strip of rubber or other suitable material may be placed along the edge of the panel to contact with the window.

In order to hold the glass steady when it has been swung out of the frame or window opening there is provided a stabilizing arm 46 which is in the form of a flat bar. The metal frame surrounding the glass panel 10 has formed therein upon the inner side a recess 47 in which at one end, one end of the bar 46 is pivotally mounted so that the bar may be swung around to position in the recess and thus be entirely out of the way when the window panel is in the frame opening.

Upon the sill of the window opening there is a lock for the bar 46 which is in the form of a block 48 having a slot 49 cut horizontally therein from one edge. Into this slot the stabilizing arm 46 may be slipped and it is held therein against movement by the screw 50 which threads downwardly through the top of the block into the slot 49.

Secured in any suitable manner to the glass panel 10 adjacent the rear edge thereof, is a rubber ring 51 which may be employed for drawing the panel tightly into the window opening.

In the operation of the present window structure if the glass panel is in lowered position in the chamber 3 the shaft 17 and gear 18 may be rotated through the medium of the crank 24 to raise the panel into the window opening, the gear 18 being in mesh with the rack 12. If the window is to be raised only so as to close the window opening rotation of the crank may be stopped as soon as the top edge of the glass panel or the metal frame in which it is mounted comes into contact with or partly enters the curtain clip 44. When in this position the lower edge of the panel will remain in the slot 4. In this position also the pin 14 upon the post 8 will be part way into the longitudinally extending portion of the bayonet slot 15. If the glass panel is to be left in this position then the band 26 may be tightened in the manner previously described to grip the drum upon the shaft 17 so that the panel cannot gravitate back into the chamber therebeneath.

If the glass panel is to be swung from the

window opening the securing band 26 is released and the crank 24 turned the same as when raising the window. This then forces the top edge of the glass panel upwardly securely into the clip 44 and raises slightly the top molding 30. At the same time the pin 14 moves into the bottom of the bayonet slot 15 and the gears 19 and 20 come into mesh. Continued rotation of the crank then causes rotary motion to be imparted to the sleeve 13 through the gears 19 and 20 so that the rack 12 and the glass panel will be swung outwardly, the pressure of the top and rear edges of the panel against the moldings causing the latter to move into their respective channels so that the panel may pass. Since the top edge of the panel 10 is firmly engaged by the clip 44 it will be readily seen that the shade 40 will be drawn from its roller 37 so that the space between the top edge of the window panel and the window opening frame will be covered. The stabilizing arm 46 may then be placed in the proper position for holding the glass panel against movement. Upon returning the panel to position in the window opening the tongue 43 carried by the clip 44 will be forced into the slot 42 so as to hold the clip from falling from position when the glass panel is lowered, the lowering operation disengaging the top edge of the panel from the clip as will be readily understood.

In the modified construction shown in Figure 9 the top edge of the window panel 10^a engages in a clip 44^a which has an inwardly and downwardly inclined tongue formed along its inner face as indicated at 43^a. The chamber 36^a in which the shade or curtain 37^a is made has a slot 42^a formed in the wall adjacent the clip 44^a. The lower edge of this slot projects slightly between the upper edge thereof to form a flange having a broad inwardly and downwardly inclined top surface over which the tongue 43^a engages. As shown in Figure 9 the free edge of the curtain 37^a is attached directly to the edge of the tongue 43^a so that when the tongue is drawn away from the wall in which the slot 42^a is formed, when the panel is swung outwardly, the shade will be unrolled and also drawn out with the panel.

Having thus described my invention, what I claim is:—

1. A window structure of the character described, comprising a window frame, a glass panel within said frame, means for vertically shifting the panel to effect its removal from the frame, means for swinging the panel from its frame upon a pivotal axis extending longitudinally of one edge thereof and a single control element for actuating both of said means.

2. A window structure of the character described, comprising a window opening frame, a chamber disposed beneath the frame and in communication therewith through a slot, a

glass panel disposed in the frame, means for lowering said panel through said slot into said chamber, means for swinging the panel from the window opening on a pivotal axis disposed adjacent one vertical edge of the panel and a single control element for actuating both of said means.

3. A window structure of the character described, comprising a window opening frame, a chamber disposed beneath the frame and in communication therewith through a slot, a glass panel disposed in the frame, means for lowering said panel through said slot into said chamber, means for swing-

10 15 20 25 30 35 40 45 50 55 60 65 70 75 80 85 90 95 100 105 110 115 120 125 130

ing the panel from the window opening on a pivotal axis disposed adjacent one vertical edge of the panel, and a shade connected to the top edge of said panel and adapted to be drawn out upon the swinging of the panel to cover the space between the said top edge and the adjacent frame.

4. In a window structure of the character described, a window opening frame, a glass panel within the frame, a vertical pivotal support for said panel comprising a post mounted in the frame and a sleeve carried by the panel and surrounding said post, a chamber disposed beneath the window opening and in communication therewith, said sleeve being longitudinally shiftable on said post, and means whereby said panel may be moved vertically into or out of said chamber.

5. In a window structure of the character described, a window opening frame, a glass panel pivotally mounted within the frame to swing about an axis parallel with one edge thereof for the removal of the panel from the frame, and moldings pivotally mounted in the frame designed to cover certain edges of the panel when the same is in the frame, said moldings yielding for the swinging of the panel.

6. In a window structure, a window opening frame, a glass panel mounted in said frame, a pivotal mounting for said panel permitting the same to swing in a horizontal plane, an outside molding at the top and free vertical edge of said panel, said top and edge moldings normally covering the adjacent edge of the panel and being pivotally mounted to permit the panel to swing out of its frame, and a curtain mounted in the top of said frame and connected at one edge with the top of the panel to be drawn to horizontal position when the panel is swung outwardly.

7. In a window structure, a window opening frame, a glass panel mounted in said frame, a pivotal mounting for said panel permitting the same to swing in a horizontal plane, an outside molding at the top and free vertical edge of said panel, said top and edge moldings normally covering the adjacent edge of the panel and being pivotally mounted to permit the panel to swing out of its frame, a curtain mounted in the top of said frame

and connected at one edge with the top of the panel to be drawn to horizontal position when the panel is swung outwardly, a chamber disposed beneath said window opening and in communication therewith to receive the panel, means for shifting said panel vertically for movement into or out of said chamber, and means for automatically disengaging the top edge of said panel from said curtain when the panel is lowered into the chamber.

8. A window structure of the character described, comprising a frame, a chamber located beneath the frame, a window panel within the frame, said frame having a recess through the bottom thereof to permit movement of said panel into said chamber, a post disposed vertically adjacent one side of said frame, a rack bar carried by said frame at one side, a sleeve connected to said rack bar and designed to slidably receive said post, a gear element mounted upon the lower end of said sleeve, a pair of gears mounted in said chamber beneath the frame, one thereof arranged for engagement with said rack and the other arranged for engagement with said first mentioned gear, and means for rotating said last mentioned gears, one of said pair of gears and the gear carried by said sleeve being designed to mesh upon the lifting of the panel into said frame whereby the panel will be swung laterally from the frame.

9. A window structure of the character described, comprising a frame, a chamber located beneath the frame, a window panel within the frame, said frame having a recess through the bottom thereof to permit movement of said panel into said chamber, a post disposed vertically adjacent one side of said frame, a rack bar carried by said frame at one side, a sleeve connected to said rack bar and designed to slidably receive said post, a gear element mounted upon the lower end of said sleeve, a pair of gears mounted in said chamber beneath the frame, one thereof arranged for engagement with said rack and the other arranged for engagement with said first mentioned gear, means for rotating said last mentioned gears, one of said pair of gears and the gear carried by said sleeve being designed to mesh upon the lifting of the panel into said frame whereby the panel will be swung laterally from the frame, and means for securing said panel against movement from a desired position.

10. In a window structure of the character described, a frame having a slot through the lower side thereof, a chamber disposed beneath the frame and in communication therewith through said slot, a glass panel within said frame, a post disposed vertically adjacent one side of the panel, a rack bar carried by said panel, a sleeve carried by said rack bar and receiving said post for longitudinal movement thereon, a bevel gear carried upon

the lower end of said sleeve, a horizontal shaft disposed in said chamber, a pair of gears carried upon said shaft, one thereof being a bevel gear and the other a spur tooth gear, 5 said spur tooth gear engaging said rack when the panel is disposed in the window frame or in the chamber, said bevel gears being in mesh when said panel is raised to a predetermined position, means coupling said post and sleeve 10 for limiting the outward swinging movement of the panel, and means for rotating said shaft.

11. In a window structure of the character described, a frame having a slot through the lower side thereof, a chamber disposed beneath the frame and in communication therewith through said slot, a glass panel within said frame, a post disposed vertically adjacent one side of the panel, a rack bar carried by said panel, a sleeve carried by said rack bar and receiving said post for longitudinal movement thereon, a bevel gear carried upon the lower end of said sleeve, a horizontal shaft disposed in said chamber, a pair of 25 gears carried upon said shaft, one thereof being a bevel gear and the other a spur tooth gear, said spur tooth gear engaging said rack when the panel is disposed in the window frame or in the chamber, said bevel gears being in mesh when said panel is raised to a predetermined position, means coupling said post and sleeve for limiting the outward swinging movement of the panel, means for rotating said shaft, and a brake element 30 designed to secure said shaft against rotation.

35 12. In a window structure, a frame, a glass panel within the frame, means for shifting said panel vertically with relation to the frame, means for swinging said panel on a vertical pivot for removal from the frame, a curtain mounted upon a spring roller within the upper part of said frame, and means for detachably connecting said curtain with the top of said panel.

40 45 13. In a window structure, a frame, a glass panel within the frame, means for shifting said panel vertically with relation to the frame, means for swinging said panel on a vertical pivot for removal from the frame, a curtain mounted upon a spring roller within the upper part of said frame, means for detachably connecting said curtain with the top of said panel, and means for automatically securing an edge of the curtain to the frame when the panel is to be lowered, to maintain said curtain edge in a predetermined position after the lowering of the panel from the frame.

50 55 60 65 14. In a window structure of the character described, a frame, a panel disposed in said frame, means supporting said panel whereby the same may be swung about a vertical pivot from the frame, a spring controlled roller of tapered formation housed in the upper part 66 of said frame having the smaller end disposed

adjacent the pivot side of said panel, said roller being supported horizontally for rotation, a shade mounted on said roller, means whereby the shade may be drawn from the roller to the exterior of the frame, and means 70 for connecting said shade with the top of said panel whereby the shade will be drawn outwardly as the panel is swung from its frame.

15. In a window structure of the character described, a frame having a chamber therebeneath and a sill slot establishing communication between the interior of the frame and the chamber, a panel disposed in said frame, means for effecting both vertical and horizontal movement of said frame, the vertical 75 movement of the frame being through said sill slot, a chamber formed horizontally in the upper part of the frame, a rolled shade mounted within the horizontal chamber, one wall of said chamber having a slot there- 80 through through which said shade may be drawn, the shade being rotatably mounted in its chamber, a resilient clip-like body attached to said shade and disposed in the upper part 85 of the frame, said body having a tongue formed along the side adjacent the slotted wall of the horizontal chamber, and a flange formed longitudinally of the slotted wall of the horizontal chamber, adjacent said slot, to be engaged by said tongue, said clip-like body 90 being disposed to frictionally receive the top edge of said panel when the same is raised to the limit of its movement in the frame.

16. In a window structure of the character described, a frame having a chamber therebeneath and having a sill slot establishing communication between the interior of the frame and the chamber, a panel disposed in said frame, means for selectively moving said panel vertically and horizontally, the vertical 100 movement of the panel being through said slot, a chamber formed horizontally in the top part of the frame, a spring actuated shade and roller mounted in the horizontal chamber, one wall of said chamber having a recess 105 therein through which the shade may be drawn, an elongated clip-like resilient member carried by said shade and located outside the said chamber, in the frame, a tongue formed integral with said clip-like member 110 projecting laterally therefrom, and means formed in the upper part of the frame for contact with said tongue to prevent vertical movement of the same and the clip, said clip being disposed to frictionally receive the top 115 edge of the panel when the same is shifted to the limit of its movement vertically in the frame.

17. In a window structure of the character described, a frame having a chamber therebeneath and a sill slot establishing communication between the interior of the frame and the chamber, a panel disposed in the frame, a vertical shaft disposed in one side of the frame, a sleeve forming an inseparable part 120 125 130

of the panel at one side thereof and oscillatably receiving said shaft, a bevel gear carried in the lower end of said sleeve, a bayonet slot formed in the other or upper end of said sleeve and having an outwardly flaring entrance portion, a pin carried by the shaft adapted to enter said slot, rack and pinion means for vertically shifting the panel through said slot, a pinion gear arranged to rotate concentrically with the pinion of said rack and pinion means and to engage the first mentioned gear upon the completion of the vertical movement of the panel, and means for actuating said pinion and the gear rotating therewith, said pin entering and locking in said bayonet slot at the completion of the vertical movement of the pinion and the meshing of the bevel gears.

In testimony whereof I hereunto affix my
signature.

ELMER J. KIRCHOFF.
